THREE-DIMENSIONAL PLASTIC PANEL

Gerald A. Woodman, 2216 Duxbury Circle,
Los Angeles, Calif. 90034

Filed Aug. 22, 1966, Ser. No. 3,547

Term of patent 14 years

(Cl. D54—2)

FIG. 1.

FIG. 2.

FIG. 3.

FIG. 4.

FIG. 5.

FIG. 1 is a top plan view of a plastic panel constructed in accordance with my new design;

FIGS. 2, 3 and 4 are sectional views of the panel respectively taken on the lines 2—2, 3—3 and 4—4 shown in FIG. 1; and

FIG. 5 is an enlarged top plan view of a portion of the panel shown in FIG. 1.

I claim:

The ornamental design for a three-dimensional plastic panel, as shown and described.
